HYDRAULIC PRESS WITH CONTINUOUSLY ROTATING DIAL

William A. Fletcher, Basil S. Sample, and Max E. Todd, Anderson, Ind., assignors to General Motors Corporation, Detroit, Mich., a corporation of Delaware

Application September 5, 1946, Serial No. 695,000

2 Claims. (Cl. 113—45)

1

This invention relates to presses for performing operations on work-pieces which are placed on workholders moved by a conveyor from a loading station to a position under the ram of a press. A press of this type is commonly known as a dial feed press, the conveyor being a rotatable table or dial which is moved intermittently. During the rest period of the dial, the ram of the press moves a tool against the workholder underneath.

When handling certain kinds of work-pieces, it is not always convenient or practical to secure them to the workholders in a manner such that they will always remain in place upon the workholders during the starting and stopping of the conveyor or dial as it carries the work from the loading station to the work station underneath the press tool.

Therefore, it is an object of the present invention to provide a press having a continuously moving conveyor or dial and to provide for movement of the support for the press tool laterally with the dial during a portion of the dial movement so that the tool will remain in alignment with the work while moving toward it. Accordingly, the disclosed embodiment of the invention comprises a conveyor such as a dial, carrying a plurality of workholders, means for moving the dial continuously, a ram for supporting a tool movable into engagement with the work on a workholder, means for moving the ram toward and away from the work, means for causing the ram to move laterally with the conveyor during a portion of its movement when the tool carried by the ram moves into engagement with the work and means for returning the ram laterally to a starting position.

The further objects and advantages of the present invention will be apparent from the following description, reference being had to the accompanying drawings wherein a preferred embodiment of the present invention is clearly shown.

In the drawings:

Figs. 1 and 1A together constitute a plan view of a press embodying the present invention.

Fig. 2 is a front elevation;

Fig. 3 is a sectional view on line 3—3 of Fig. 1;

Fig. 3A is the top view of a piston rod shown in Fig. 3;

Fig. 4 is a side elevation partly in section, the part in section being on the line 4—4 of Fig. 2;

Fig. 5 is a diagram of hydraulic circuits.

Referring particularly to Fig. 3, there is a base 10, or table top which is supported above the floor level in any suitable manner, not shown. Base 10

2

10 supports a fixed rod 11 and a roller thrust bearing 12 which supports one arm 13 of a C-shaped frame 15 having an arm 14 also journaled on the rod 11. Upward movement of the C-frame 15 is restricted by a roller thrust bearing 16 clamped against a shoulder 17 of the rod 11 by nuts 18 threaded on the rod and located in a recess 19 closed by a cover 20 attached to the frame 15.

10 A dial 21 is journaled on the rod 11 and is located between the arm 13 of the C-frame 15 and a collar 22 pinned to the rod 11. The weight of the dial 21 is transmitted to the base 10 through a thrust ball bearing 23, the hub of arm 13 of C-frame 15 and the thrust roller bearing 12. The dial 21 carries a plurality of workholders equiangularly spaced adjacent the periphery of the dial. One of these workholders is represented by the block 25 which obviously would be shaped to conform to the work-pieces. When the workholder 25 is located for the press operation, it is above the plane surface 26 of a pad provided by the arm 13 of C-frame 15 so that the pressure exerted by the press tool upon the work tending 25 to deflect the dial will cause the dial to be pressed against the surface 26.

The dial 21 is rotated continuously by an electric motor, not shown. Referring to Fig. 2, the motor is connected by a belt drive with a pulley 30 which, through a speed reducing mechanism 31, drives a shaft 32 connected by a coupling 33 with a shaft 34 journaled in bearings 35 and 36 (Fig. 4) supported by a bearing frame 37 attached to the base 10. The shaft 34 provides a pinion 38 meshing with a gear 39 attached to the underside of the dial 21. A gear ratio between the shaft 34 and the dial 21 corresponds to the number of workholders 25 on the dial. For example, if the dial carries twelve workholders, the speed ratio of the shaft 34 and dial 21 is 12 to 1. Therefore, the pinion 38 may have twelve teeth and the dial 144 teeth. For each revolution of the shaft 34 the dial will rotate 30° which is the angular spacing of the twelve workholders on the dial.

45 Since the shaft 34 makes one revolution during each press cycle it may be used to control the movement of the press ram to be described. Accordingly, the shaft 34 drives a cam 40 which engages a roller 41 carried by a valve rod 42 of an oil pressure distributing valve 43 to be described. Valve 43 is supported by bracket 44 attached to the table 10, said bracket supporting also the speed reducing gear 31.

The C-frame 15 includes a tubular part 50 (Fig. 3) which carries a sleeve 51 and a head 52

which screws 53 attach together with the sleeve 51 to the frame portion 50. The head 52 has a threaded central opening 54 which receives a threaded portion of a piston rod 55 which is normally fixed but which can be vertically adjusted by turning the piston by a wrench applied to flats 56 at the upper end thereof. When the adjustment is made rotation of the piston is prevented by a lock nut 57.

The lower end of rod 55 provides a piston 58 fitting the inner wall of a cylinder or ram 59 which is guided for vertical movement by sleeve 51. Axial rotation of the cylinder 59 is prevented by a key 60 which slides in a vertical groove 62 provided by the sleeve 51. The key 60 is fixed to the cylinder 59 by a nut 61 which has sliding fit with the rod 55 and which closes the upper end of the cylinder 59. The rod 55 is provided with passages 64 and 65 into which pressure oil is distributed by the valve 43 (Fig. 4). When passage 64 is connected with the pressure source and passage 65 is connected with drain, cylinder 59 will move down until the lower end of nut 61 engages the upper side of the piston 58. When passage 65 is connected with the pressure source and passage 64 with drain, the cylinder 59 will move up until the nut 61 engages the flange 52a of head 52. The frame 15 provides an oil seal 66 for preventing the passage of oil downwardly from the lower end of the cylinder 59. The oil which accumulates above the seal is conducted through passage 67 connected by a pipe, not shown, with drain or tank.

The lower end of the cylinder or ram 59 provides for attachment thereto of a tool for performing an operation upon the workpieces carried by the workholders. The tool is not shown but it will be understood to be one which is designed to perform a particular operation.

The head 52 supports a valve 70 moved into engagement with a valve seat 71 by a spring 72 which surrounds the valve stem and is confined between a surface 73 of the head and a washer 74 retained on the valve stem by a pin 75. The head 52 has a hole 76 which provides clearance around the valve stem. The valve 70 moves in a recess 77 closed by a nut 78. A passage 79, which is connected with one of the pressure lines to the piston in a manner to be described, connects with the recess 77 above the valve seat 71. Below the valve seat, the recess 77 connects with a passage 80 connected in a manner to be described with drain or tank. When the cylinder 59 is up, as shown in Fig. 3, valve 70 is open. Valve 70 is closed by the spring 72 after the cylinder 59 has moved down a certain amount.

Since the dial is moving continuously it is necessary that work tool move laterally with the dial while the tool is moving into engagement with the work. For this purpose the dial is provided with pins 90 (Figs. 1 and 4) equi-angularly spaced and equal in number to the number of workholders 25. Each pin 90 engages a dog 91 carried by the C-frame 15. Dog 91 is a lever attached to a shaft 92 which extends through a spacing collar 93 (Fig. 4) and through bearings 94 in a bearing bracket 95 attached to the frame 15. A spring 96 which surrounds the spacer 93 urges the dog 91 clockwise as viewed in Fig. 1 or looking in the direction of arrow 97 (Fig. 4), said motion being arrested when a lever 98 attached to the lower end of the shaft 92 engages a stop pin 99 fixed to the bracket 95. Lever 98 carries a roller 100 for engagement by a cam surface 101 provided by a bracket 102 having a slot

103 through which screws 104 extend and which are threaded into the table 10. The slot provides an adjustment of the bracket 102.

The dial 21 rotates counterclockwise as viewed in Fig. 1. Therefore, when the pin 90 engages the dog 91 the C-frame 15 will move laterally with the dial about the dial axis O. Fig. 1 shows C-frame 15 in a position represented by its center line C—O which is between its limits of travel. At that instant, the pin 90 which engages the dog 91 is on line B—O and the pin 90' which is next to engage the dog is on line A—O. At a position to the right of C—O the pin 90 engaged this dog 91 and started movement of the frame 15. As the frame 15 starts moving with the dial 21, cam 40 which rotates clockwise as viewed in Fig. 1, causes the valve rod roller 41 to move up (Fig. 1) to cause valve 43 to be conditioned for effecting downward movement of the ram 59. A latch to be described maintains the valve 43 in that condition independently of the cam 40. Fig. 1 shows that the cam 40 is about to leave the roller 41. At a position of the frame 15 to the left of B—O, through the coaction of surface 101 of bracket 102 and roller 100, the dog 91 will be moved counterclockwise away from the path of movement of the pin 90 so that the frame 15 can be returned by means to be described to a starting position at the right of C—O, and the dog 91 will be returned by spring 96 (Fig. 4) to a position when the dog will be engaged by the next pin 90' which had been moving to the left of A—O while the frame 15 had been moving to the left of C—O.

Before the disengagement of the dog 91 from roller 90, the cam 40 had entirely released the roller 41 so that by means responsive to the completion of the operation upon the work by the ram supported tool, the valve latch is retracted in a manner to be described and a spring causes the valve 43 to be conditioned for causing the ram 59 to be lifted.

The return of the frame 15 from a position to the left of C—O to a position to the right of C—O is effected by the instrument 110 commonly known as a "door closer." The door closer 110 comprises a cylinder 111 having a mounting pad 112 attached to a bracket 113 supported by the table or base 10 (Fig. 2). A spring, not shown, within the cylinder 111 urges an arm 114 clockwise (Fig. 1) about its axis 115. Arm 114 is pivotally connected at 116 with an arm 117 pivotally connected at 118 with a lever 119 pivotally connected at 120 with a bracket 121 which screws 122 attach to the frame 15. The door closer 110 includes a pneumatic or hydraulic check which retards the clockwise return movement of the frame 15. The check can be adjusted to vary the time of return of the frame 15 to a starting position. The frame 15 is timed to return to its starting position just before the next pin 90' moves into engagement with the dog 91. Consequently the oscillation of the frame 15 is almost continuous. The object is to return the frame 15 to its starting position just in time for the dog 91 to be engaged by the next pin 90' which is moving counterclockwise from the position on line A—O (Fig. 1).

Fig. 5 is a diagram of the hydraulic circuits of the press. Fig. 5 shows an oil supply tank 130 connected by pipe 131 with the inlet of a motor driven pump 132 having an outlet connect by pipe 133 with a passage 134 through a pressure relief valve unit 135 having a valve body 136 which provides a cylinder 137 closed by cover 138. The

cylinder 137 receives a piston 139 which provides a valve 140 which is held upon a seat 141 by the force of a spring 143 and by the pressure of oil above the piston 139, said oil entering through a small passage 142. A central passage 144 in the rod of piston 139 leads from a chamber 145 in the head 138 to a passage 146 below the seat 141 connected by pipe 147 with the tank. The head 138 is provided with a passage 148 connecting cylinder 137 with a valve seat 149 normally closed by ball valve 150 urged against the seat by a spring 151, the pressure of which is adjusted by screw 152.

The passage 134 is connected by pipe 154 with port 155 provided by the body 156 of the valve unit 43. A port 157 is connected by pipe 158 with passage 64 in the piston rod 55. A port 159 in body 156 is connected by pipe 160 with passage 65 in the piston rod 55. The valve body 156 provides exhaust ports 161 and 162 connected by a passage 163, connected by pipe 164, connected with pipe 147. Pipe 165 connects pipe 160 with passage 79 leading into the chamber 77 of the head 52 as shown in Fig. 3. Passage 80 is connected by pipe 166 with pipe 147. The valve rod 42 provides a land 170 for controlling ports 157 and 161 and a land 171 for controlling port 159 and 162. A spring 172 urges the valve rod 42 toward the right so that the roller 41 (Fig. 4) may engage the cam 40. The valve rod provides a shoulder 173 for engagement by a pin 174 extending from a piston 175 received by a cylinder 176 provided by the valve body 156. A spring 177 urges the piston 175 upwardly in Fig. 5. A pipe 178 connects passage 148 of the valve unit 135 with the cylinder 176.

Fig. 5 shows the status of the valve 43 after the cam 40 (Figs. 1 and 4) has moved the valve rod 42 left into the position shown in Fig. 5 to permit the spring 177 to push the pin 174 between the shoulder 173 and the land 171. The valve rod 42 is then held in that position temporarily independently of the cam action. The pump is then connected by passage 134 and pipe 154, port 155, 157 and pipe 158, passage 64 with the lower side of piston 58 thereby causing the cylinder or ram 59 to move downwardly to cause the tool carried thereby to engage the work. When the tool has completed its operation, downward movement of the ram 59 ceases and pressure increases in the passage 134 of the valve unit 135. When the pressure exceeds the limit for which the spring 151 is adjusted, the ball valve 150 opens and pressure above the piston 139 decreases because oil can discharge from the cylinder 137 through the passages 148 and 144 faster than it can enter through the smaller passage 142. Then the spring 143 is no longer able to maintain the piston 139 down; and the valve 140 lifts from the seat 141 thereby permitting the pump to discharge back to the tank through the pipe 147.

When pump pressure is thus relieved the pressure in the cylinder 176 of the valve unit 43 decreases and the pressure within the valve body 156 acting upon the stop pin 174 and the upper end of the piston 175 is sufficient to overcome the spring 177 thereby pushing the pin 174 away from the shoulder 173 whereupon the spring 172 will move the valve rod 42 to the right. The cam 40 is so constructed that before downward movement of the ram is arrested the low land of the cam will be adjacent the roller 41 so that movement of rod 42 to the right by the spring 172 can take place. Then the rod 42 is in position so that land 171 blocks port 162 and connects ports

155 and 159 while land 170 blocks communication between ports 155 and 157 and permits connection between port 157 and 161. Therefore, while piston rod passage 64 is connected by the pipe 164 with tank, piston rod passage 65 is connected with pipe 154. Therefore, pressure fluid is being admitted to the upper side of the piston 58 while the lower side is connected with the tank. Therefore the cylinder or ram 59 will move up. As it does so, it lifts the valve 70 for the purpose of relieving pressure on the pump independently of the action by the valve unit 135. Because the piston rod 55 and the head 52 are movable laterally with the C-frame 15, the pipes 158, 160, 165 and 166 are provided respectively with flexible sections 158a, 160a, 165a and 166a.

The attendant who loads the workpieces on the workholders usually sits in front of the dial as viewed in Fig. 2, which is below Fig. 1. It has been found that there is no disadvantage to the attendant to load a workholder on a continuously moving dial. The attendant soon becomes accustomed to the steady movement of the dial. In fact it is less trying to load a steady moving dial than one which stops and starts intermittently. Since more than normal loading time may be consumed in loading a workholder it may happen that the attendant is still loading the dial when it suddenly starts moving. He may not then be ready to release the part he has placed on the workholder, and the part may become dislodged before he releases hold of it. With a continuously moving dial this difficulty is not present. Furthermore, there is no jerking of the dial by starting and stopping such as to dislodge the pieces which the attendant has placed upon the workholder. Therefore, for certain kinds of work where it is not practical or convenient to clamp the workpieces to the workholder or secure them in a manner which will resist any jerking of the dial, a press having a continuously moving dial is a decided advantage.

The guard 125 (Fig. 3) which is attached to the table 10 protects the attendant from the gear 39.

While the embodiment of the present invention as herein disclosed, constitutes a preferred form, it is to be understood that other forms might be adopted, all coming within the scope of the claims which follow.

What is claimed is as follows:

1. A press comprising a conveyor carrying work holders for supporting work pieces, means for moving the conveyor continuously, a ram for supporting a tool which engages a work piece when aligned with the ram, an hydraulic servomotor for moving the ram toward and away from the work piece in alignment therewith, an oil supply tank, a pump for forcing oil from the tank under pressure to the hydraulic means, a valve for controlling the application of pressure oil to the servomotor, said valve being actuatable into a status for causing the ram to move toward the work piece and being actuatable into another status for causing the ram to move away from the work piece, cam operated means coordinated with movement of the conveyor for causing the valve to be actuated into the first status, a spring for causing the valve to be actuated into the second status, a latch for temporarily holding the valve in the first status, a pressure relief valve responsive to the application of a certain pressure by the ram on the work piece for causing the load on the pump to be relieved, means responsive to action of the pres-

sure relief valve for causing retraction of the latch whereby the spring can actuate the valve into the second status, means for causing the ram to move laterally with the conveyor during a portion of its movement when the ram is aligned with the work piece, and means for causing lateral return movement of the ram to a starting position.

2. A press comprising a conveyor carrying work holders for supporting work pieces, means for moving the conveyor continuously, a ram for supporting a tool which engages a work piece when aligned with the ram, an hydraulic servomotor for moving the ram toward and away from the work piece in alignment therewith, an oil supply tank, a pump for forcing oil from the tank under pressure to the hydraulic means, a valve for controlling the application of pressure oil to the servo-motor, said valve being actuatable into a status for causing the ram to move toward the work piece and being actuatable into another status for causing the ram to move away from the work piece, cam operated means coordinated with movement of the conveyor for causing the valve to be actuated into the first status, a spring for causing the valve to be actuated into the second status, a latch for temporarily holding the valve in the first status, a pressure relief valve responsive to the application of a certain pressure by the ram on the work piece for causing the load on the pump to be relieved, means responsive to action of the pressure re-

lief valve for causing retraction of the latch whereby the spring can actuate the valve into the seond status, a third valve actuated in response to movement of the ram away from the work piece for causing the load on the pump to be relieved, means for causing the ram to move laterally with the conveyor during a portion of its movement when the ram is aligned with the work piece, and means for causing lateral return movement of the ram to a starting position.
